UNITED STATES PATENT OFFICE

2,475,231

VOLATILE LIQUID DISPENSER

Victor William Gelatka, Chicago, Ill.

Application November 28, 1947, Serial No. 788,617

5 Claims. (Cl. 299—24)

1

This invention relates to volatile liquid dispensers and more particularly to sachet blocks or devices for dispensing pleasant odors in the home, office, churches, or elsewhere. A further object is to provide a volatile liquid dispenser that is attractive in appearance, of novel design and structure, inexpensive to manufacture, durable in use and efficient in operation.

Other objects, novel features and advantages of arrangement, construction and design comprehended by the invention are hereinafter more fully pointed out or made apparent from the following description of a preferred embodiment as illustrated in the accompanying drawing wherein like reference characters denote corresponding parts throughout.

In the drawing:

Fig. 1 is a top plan view of a volatile liquid dispenser according to the instant invention.

Fig. 2 is a view of Fig. 1 in elevation.

Fig. 3 is a substantially central vertical sectional view through Fig. 1.

Fig. 4 is a plan view of the base of the dispenser, the block portion proper being omitted.

Fig. 5 is a plan view of the block portion removed from the base and inverted.

Fig. 6 is a central vertical sectional view through a modified form of dispenser, a container employed being shown in dotted lines.

Fig. 7 is a view of a type of pronged ring employed in the modified form, the block proper being denoted in dotted lines, and.

Fig. 8 is a view similar to Fig. 7 but of a clamping member employed.

Referring now to Figs. 1 to 5 inclusive the reference numeral 1 denotes a substantially square base formed with a square recess 2 opening in its top face and of a depth about one half the base thickness.

The said recessed portion 2 has a centrally disposed round materially contracted recess extension 3 in which is received a small vial 4, preferably of a diameter but slightly less than that of recess 3, containing a liquid perfume. Freely received on end in the base recess is an oblong hollow block 5, the block cavity increasing in diameter from one end of the block to the other and at its wide end opening in the end face of the block, the diameter of the block cavity being greater throughout most of its extent than that of the vial which is received therein. The block is formed across each outer face with a shoulder 6 spaced inwardly from its open end a distance slightly less than the depth of the base recess 2, the four shoulders 6 being in a common plane

2

and the block of such diameter relative to said recess that the walls of the latter will support the block upon said shoulders in spaced relation to the bottom surface of the recess as clearly shown in Fig. 3. The block and base are formed of gypsum or a like porous material and both are coated with gilt 7 or a like decorative pore-filler upon their side portions. Each side of the block is decorated preferably by a fanciful figure 8 and imbedded in the block material at its closed end is the wick 9 depending into the contents of the vial 4.

Referring now to Figs. 6, 7 and 8 the block 10 has a metal or like pronged ring 11 imbedded therein at a distance spaced inwardly slightly from its open end, the inner edge of the ring extending very slightly into the block cavity for releasable engagement with the four resilient spring hooks 12 operatively carried by a second 20 pronged ring 13 of smaller diameter than the ring 11, said ring 13 being received in and carried by the base material, the hooks 12 yieldingly securing the block and base together so that the dispenser may be picked up by hand by the block 25 without separating same from the base. These members may be readily separated or pulled apart when desired and again engaged by "snapping" the hooks and ring 11 into engagement with each other.

30 Attention is called to the fact that, if desired, the block may be removed from the base, inverted and rested upon its closed end and then filled with perfume which will be absorbed and thereafter evaporated at ordinary room temperatures to provide the desired pleasant odor. This is true of the dispenser in both forms disclosed. When used in this manner the wick is not necessary.

What is claimed is:

1. In a volatile liquid dispenser, a hollow block 40 of porous material open at one end, a recessed base receiving and supporting the open end of the hollow block, a vial disposed in the base recess and received in said block, and a wick having one end imbedded in the closed end of said block and received in said vial.

2. In a volatile liquid dispenser, a hollow block 45 of porous material open at one end, a coat of pore-closing material covering the major portion of the exterior surface of said block, a recessed base receiving and supporting the open end of the hollow block, yielding coupling means connecting said block and base, a liquid container carried by said base, and a wick carried by said block received in said container.

55 3. In a volatile liquid dispenser, a hollow block

of porous material open at one end, a recessed base receiving the open end of said block, pore-closing material covering the major portion of the exterior surface of said block and base, a liquid container carried by said base, a ring imbedded in said block in short spaced relation to the open end thereof, and yielding ring-engaging means carried by said base.

4. In a volatile liquid dispenser, a hollow block of porous material open at one end, an external peripheral shoulder upon said block spaced inwardly from the open end thereof, a recessed base receiving said block at its open end, the depth of said base recess being less than the distance of said shoulder from said block open end, the wall of said base recess formed complementary to the open end of said block and engaging said block shoulder, a liquid container carried by said base and received in said block, and a wick

carried by said block and extending into the interior of said container.

5. In a volatile liquid dispenser, a hollow block of porous material open at one end, a recessed base receiving the open end of said block, an inwardly projecting and circumferentially extending ring imbedded in said block in short spaced relation to the open end thereof, a second ring secured in the recessed portion of said base in a plane substantially parallel to the first said ring, resilient hooks carried by said second ring yielding in locking engagement with said first named ring, a liquid container carried by said base, and a wick carried by said block disposed in said container.

VICTOR WILLIAM GELATKA.
